[57] CLAIM

The ornamental design for a "purse," as shown and described.

DESCRIPTION

FIG. 1 is a right side elevational view of a "purse," showing my new design;

FIG. 2 is a front elevational view thereof;

FIG. 3 is a top plan view thereof, with a portion of the upper part of the carrying strap being omitted, to better show the top of the purse's body;

FIG. 4 is a left side elevational view thereof;

FIG. 5 is a rear elevational view thereof; and,

FIG. 6 is a bottom plan view thereof.
